By

UNITED STATES PATENT OFFICE.

ZACHARY T. MILLER, OF BLISS, OKLAHOMA.

BLINDER.

1,406,676.

Specification of Letters Patent. Patented Feb. 14, 1922.

Application filed April 14, 1921. Serial No. 461,215.

To all whom it may concern:

Be it known that I, ZACHARY T. MILLER, a citizen of the United States, residing at Bliss, in the county of Noble and State of Oklahoma, have invented certain new and useful Improvements in Blinders, of which the following is a specification, reference being had therein to the accompanying drawing.

10 It is an object of this invention so to form a blinder of one piece of sheet material that it may be associated adjustably with the cheek or other strap of a bridle without employment of other parts.

15 The invention further provides for the economical production of blinders by the stamping of blanks from sheet metal and the bending thereof to form the complete articles, which have guideways for the straps 20 and means for holding them adjustably therein.

25 When considered in connection with the description herein, the characteristics of the invention will be apparent from the accompanying drawing, forming part hereof, wherein an embodiment of the invention is disclosed, for purposes of illustration.

30 Although the disclosures herein exemplify what now is considered to be a preferable embodiment of the invention, it is to be understood that it is not the intention to be limited necessarily thereto in interpretation of the claims, as modifications and adaptations within the limits of the claims can be 35 made without departing from the nature of the invention.

Like reference characters refer to corresponding parts in the views of the drawing, of which—

40 Fig. 1 is a view of the blinder in association with a bridle-strap;

Fig. 2 is a longitudinal section thereof; and

45 Fig. 3 is a view of the blank from which the article is formed.

In the production of the article, blanks of substantially the shape shown by Fig. 3 are stamped out from bendable sheet-metal stock.

50 Such a blank includes a portion 4 to form the blinder proper, from along the strap-edge of which is cut an elongated opening

leaving strap-crossing members 5 at each end, which connect to the portion 4 an elongated portion 6, the latter portion constituting the material from which the strap guide or channel is to be formed. 55

Either before or after bending such a blank as hereinafter described, a strap-engaging member 7, such as a pin, is secured 60 at or about midway between the ends of the portion that is to be the bottom of the strap guide or channel. That member may be a headed shank having its head 7a hammered close to the under side of the material and 65 held in place by solder or other suitable means.

The blank is bent along longitudinal lines a—a and a'—a' in the sides of the portion 6 to afford upstanding flanges 8 constituting 70 the sides of the strap guideway or channel, the remaining part 9 of portion 6 constituting the bottom of the guideway or channel.

The members 5 then are bent at the line b—b over against the opposite flange 8, the 75 edge of the blinder portion thus being brought at the same time against that flange, after which the parts are soldered together at the places of contact.

An article formed in the expeditious and 80 economical manner described constitutes a combined blinder and buckle. As seen in Figs. 1 and 2, a cheek or other bridle strap 10 may be disposed in the channel under the cross members 5 and with any one of its holes 85 in engagement with the member 7.

The position of the blinder on the strap may be altered, of course, by raising the strap from the member 7 and then drawing the strap in one direction or the other in the 90 channel, the channel being open between the members 5 to permit access to the strap.

Moreover, when the strap is looped in the ring of the bit, as shown, its free end portion may be brought back into the channel and 95 any one of its holes into engagement with the member 7.

Having thus described my invention, what I claim as new, and desire to secure by Letters Patent, is—

100 1. An article of the kind described formed of a single piece of bendable sheet material and comprising a blinder having at its side a strap-guideway, said guideway being af-

forned by an elongated portion of the material constituting its bottom, side flanges, and end cross members connecting the flanges, said guideway being open between 5 said cross members, and a strap-engaging member on said bottom between said cross members.

2. The process of forming a combined blinder and buckle that includes the cutting 10 from sheet material of a blank shaped to afford a blinder portion, an elongated opening at one side thereof, and an elongated side portion joined to the blinder by cross

members, bending the marginal parts of said elongated portion to form sides of a strap-guideway, then bending the material at an edge of one of said sides to bring said cross members and an edge of said blinder portion over and into abutment with an edge of said other side and securing said edges together, and placing a strap-engaging member on said elongated portion between the sides thereof and said cross members.

In testimony whereof I affix my signature.

ZACHARY T. MILLER.
